UNITED STATES PATENT OFFICE.

ERNEST B. COBB, OF JERSEY CITY, NEW JERSEY, ASSIGNOR TO STANDARD OIL COMPANY, OF BAYONNE, NEW JERSEY, A CORPORATION OF NEW JERSEY.

MAKING LOW-BOILING OIL FROM HIGHER-BOILING PETROLEUM OR RELATED OIL.

1,322,878.

Specification of Letters Patent.

Patented Nov. 25, 1919.

No Drawing.

Application filed April 25, 1914. Serial No. 834,344.

To all whom it may concern:

Be it known that I, ERNEST B. COBB, a citizen of the United States, residing at Jersey City, in the county of Hudson and State of New Jersey, have invented certain new and useful Improvements in Making Low-Boiling Oil from Higher-Boiling Petroleum or Related Oil, of which the following is a specification.

This invention relates to obtaining oils which are composed mainly at least of hydrocarbons with boiling points normal to naphtha and the lighter end of burning oil (kerosene) (say up to 302° F. for naphtha and 302° F. to 450° F. for the lighter end of burning oil, the boiling points regarded herein as normal to the heavier end of burning oil being from 450° F. to 572° F.) by operating upon petroleum in forms (distillate and undistilled) which contains a large proportion at least of higher boiling hydrocarbons (say hydrocarbons with boiling points above 450° F.) more particularly, but not exclusively, distillate oils of this description which are mainly at least composed of hydrocarbons with viscosities too low for normal constituents of other than light grades of lubricants (say with viscosities under one hundred and seventy seconds at 100° F. with an Engler viscosimeter with which water exhibits a viscosity of fifty-three seconds at 60° F.), such as the inferior grades of burning oil (kerosene) (either finished or untreated) and the oils commonly disposed of as gas oil or fuel oil on account of their being unfit on the one hand for burning oil (kerosene) and on the other for medium and heavy lubricants; for which products there is usually a good demand at higher prices than those of gas oil or fuel oil.

In accordance with the invention, petroleum in appropriate form is distilled with anhydrous aluminum chlorid (Al_2Cl_6) in solution in (combination with) a part of the oil operated upon (useful proportions hereinafter indicated) at temperatures sufficient to split up component hydrocarbons of the oil; and the products of such distillation are fractionated to obtain oils of such grades as may be desired and obtainable.

Said distillation with anhydrous aluminum chlorid is continued to such extent as may be desired. By continuing it until a

dry or nearly dry residue remains in the still, practically the entire carbon content of the oil operated upon, except the portion which escapes as gas or as uncondensed vapors or is otherwise lost, is obtained in the forms of distillate from distilling in the presence of anhydrous aluminum chlorid and of coke respectively.

Should the distillation be terminated previously, that is to say, while the residual material is yet liquid as a whole or in substantial proportion, the carbon content of the oil operated upon can also be obtained in said forms respectively, by separating the oily portion of the residual material from the aluminum chlorid thereof and (if desired) also from the solid carbonaceous matter (if any) which may be present therein, and subjecting the hydrocarbons of said oily portion to distillation with anhydrous aluminum chlorid. The so separated oily portion can be distilled at once with anhydrous aluminum chlorid, but it would best be distilled by itself to dryness or nearly so, and the resulting distillate then be distilled with anhydrous aluminum chlorid.

The said oily portion can, however, be disposed of otherwise as may be preferred; in case it should not be desired to distil its component hydrocarbons with anhydrous aluminum chlorid.

In distilling with anhydrous aluminum chlorid the activity of the latter diminishes with the progress of the distillation; and of the temperature of the oil in distillation should be kept approximately constant, after a suitable flow of the distillate has been established, the delivery is liable to diminish down to an impracticably slow rate, and eventually to cease altogether; and this diminution (or cessation) of distillation, in distilling at constant temperature, occurs sooner the less the proportion of anhydrous aluminum chlorid employed. When, however, the fires are so regulated, and the temperature consequently of the oil operated upon is gradually so increased, as to maintain the delivery of distillate from the condenser outlet at an industrially practicable rate, I have discovered that even a limited proportion of aluminum chlorid, say not more than ten per cent. by weight of the original charge of oil operated on (less than

ten per cent. in fact) will exert its activity substantially to the end of a run, which is continued to dryness or approximately so.

The aluminum chlorid is easily separated 5 in its entirety from its original solution in a part of the oil operated upon, by washing such solution with water at say atmospheric temperature, and allowing the resulting aqueous solution of hydrated aluminum 10 chlorid to settle out below the supernatant layer of oil. I have discovered, however, that a point is attained in the progress of a distillation at which the residual material can no longer be freed entirely from aluminum 15 chlorid by washing out even with boiling water; as may be shown by the presence of more than traces of the element aluminum in a sample after the latter has been boiled say for ten minutes in water.

20 By further distillation at increasing temperature, less and less of the aluminum chlorid is found to be separable in this manner; so that eventually the major portion of the aluminum chlorid will be retained. The union with carbonaceous matter may in fact become so strong that little 25 (if any) of the aluminum chlorid can be extracted from the residual material by boiling water as aforesaid.

30 In case, therefore, the aluminum chlorid is to be recovered by washing out, it is desirable not to proceed too far with the distillation; but, in view of the fact that the farther the distillation is carried, the greater 35 the conversion effected by a given amount of aluminum chlorid, it is desirable on this account to proceed at least until the residual material attains approximately the lowest point at which practically all of the aluminum chlorid can be washed out with water.

40 Any ordinary or suitable distilling apparatus can be used. An ordinary still of horizontal cylindrical form holding say six hundred barrels of forty gallons each and 45 an ordinary water cooled condenser connected with said still by a vapor pipe will answer. The following examples are given by way of illustration and not as restricting the invention to them or to details of them.

50 Such a still may well receive a charge of about four hundred barrels of the gas oil or fuel oil mentioned, and a limited proportion, not more than about ten per cent. by weight of anhydrous aluminum chlorid. The temperature is gradually raised until distillate 55 commences to flow from the condenser outlet (which may be in say six or eight hours or thereabout from the commencement of firing); and the fires are regulated to give 60 a good flow (say fifteen to twenty barrels an hour or thereabout).

Distillation is conducted in this way to the end, or at least approximately the end of the run. The temperature of the oil in distillation 65 increases gradually, as is required in

order to distil at an industrially practicable rate. The run is terminated sooner or later, according to case.

It may, for example, be carried on until the contents of the still constitute an at least 70 approximately dry residue; or it may be terminated while the residual material is liquid in whole or in a substantial proportion. It may be terminated while the still contents are of a character to permit the practicable 75 separation of aluminum chlorid from the remaining material by washing out; or it can be carried so far that the separation, if any, which can thus be effected is not enough to be practicable.

80 At the close of the run, the heating is discontinued, and later, when the running (if any) from the condenser outlet has ceased, the residual material is removed from the still preparatory to charging the still for a 85 new run. If said residual material is sufficiently fluid, the same is advantageously withdrawn through a cooling coil.

90 The residual material can be disposed of, and the aluminum chlorid therein (or its elements) can be recovered and disposed of, in any appropriate way. The oily or other carbonaceous matter in said residual material can also be recovered and disposed of as preferred. For example, by combustion 95 of the residual material (in whatever condition) an ash consisting almost wholly of alumina is obtained, and also gases containing hydrochloric acid. If the residual material is of a character to allow a practicable 100 separation of aluminum chlorid by washing out, it is advantageously washed with water of appropriate temperature, say at or above 150° F., using as little water as will suffice, say about twenty five per cent. of the residue, or possibly a smaller amount; especially if the washing is conducted in a systematic manner by transferring the wash water from a previously washed residue to 105 residue which has not been washed to the same extent, if at all. An aqueous solution of hydrated aluminum chlorid is thus obtained, which can be disposed of in any appropriate way. By evaporation of it to

110 dryness, alumina is obtained as residue and hydrochloric acid passes off with the water vapor. If the residual material is liquid in whole or in substantial proportion, washing 115 it with water will yield an oil, as well as an aqueous solution of hydrated aluminum chlorid. The so recovered oil is advantageously distilled to dryness, or to a lesser extent, if preferred; and the distillate (separated from whatever water, if any, may pass over) is itself distilled with anhydrous 120 aluminum chlorid. The coke from distilling the recovered oil to dryness can be disposed of as may be preferred. The recovered oil 125 can be distilled at once with anhydrous aluminum chlorid, although not so advanced.

tageously, by reason of the accumulation of coke; or it can be disposed of otherwise, as may be preferred.

From the alumina and the hydrochloric acid obtained as aforesaid (or in whatever way) from the residual material anhydrous aluminum chlorid can be reconstituted by known methods. For example, anhydrous aluminum chlorid distils over when dry chlorin (which is obtainable by known means from hydrochloric acid) is passed over an incandescent mixture of coke and alumina.

Returning to the distillation of the petroleum (gas oil as mentioned) with anhydrous aluminum chlorid, it suffices to collect the distillate all in one receiver. Any solution of anhydrous aluminum chlorid which may come over with distillate is allowed to settle out and is separated for future use. The condenser and a liquid separator intermediate the condenser and the distillate receiver may well be elevated above the still, and the bottom of the separator be connected with the still by a suitably trapped pipe for conducting the aluminum chlorid solution back to the oil in distillation; while the upper part of the separator is connected with the distillate receiver.

The distillate may be washed with water and then fractionated with partial or with complete distillation by means of dry heat; or the fractionation may be performed by partial distillation in a steam still, in which case the water of condensation serves to wash the distillate. Washing the distillate with water can precede the steam stilling, if preferred; and the residual oil from partial distillation with dry heat or in the steam still can be fractionated by dry heat, or can be disposed of otherwise, as may be preferred. In some cases at least it may be best to agitate the washed distillate with sufficient alkali (caustic soda lye) to neutralize any remaining acid (hydrochloric acid) therein before fractionating by distillation. In fractionation, cuts are made to obtain oils of the desired grades, all of which may well be composed at least mainly of hydrocarbons with boiling points not exceeding 450° F. and also to obtain, if desired, higher boiling oils. The low boiling oils, say various grades of naphtha, may be finished for use or sale by giving them the customary treatment with sulfuric acid and alkali; and the burning oil (kerosene) distillate can be similarly finished. The higher boiling oils, as a whole or in such part as may be preferred, can be distilled anew with aluminum chlorid; or they can be disposed of otherwise, as may be preferred.

Good results have been obtained in a small way with an amount of anhydrous aluminum chlorid equal to about seven per cent. by weight of the oil operated upon; nine per

cent. by weight would probably give better results. The proportion can be varied within wide limits. Reduction of the proportion of anhydrous aluminum chlorid tends to lower the yield of hydrocarbons with boiling points below 450° F. Increase in the proportion of anhydrous aluminum chlorid tends to increase the proportion of such hydrocarbons; but it will probably not be worth while to exceed about ten per cent. by weight in any case. If this percentage be added to petroleum distillate (gas oil or fuel oil or other distillate) the anhydrous aluminum chlorid dissolves at appropriately elevated temperature in a part of such distillate; and the solution will form a distinct layer underneath the remainder of the distillate, if not kept in suspension therein by agitation. The anhydrous aluminum chlorid can be added to the oil in the still in solid state or in solution; or it can be placed in the still before charging the same with oil. When the still is heated the aluminum chlorid dissolves gradually in a part of the oil when the temperature suffices. Probably if enough aluminum chlorid were employed, the whole of the oil might form a solution thereof; but it is not believed that so large a proportion would be desirable, if practicable.

From gas oil or fuel oil containing some paraffin wax and of a gravity of 33.8° B., which consisted of over ninety per cent. by volume of hydrocarbons with boiling points above 450° F. and which, if distilled in the usual way in a laboratory flask, would give first runnings equal to five per cent. by volume with a gravity of 48° B., an amount of naphtha (distilling over up to 302° F.) of 67° B. equal to about twenty and a half per cent. by volume of said gas oil or fuel oil and water white burning oil (kerosene) of 45.6° B. equal to twenty nine per cent. by volume of said gas oil or fuel oil have been obtained, using about 7% by weight of anhydrous aluminum chlorid and working in a small way. These oils consisted the naphtha wholly and the kerosene mainly of hydrocarbons with boiling points not exceeding 450° F. The first 5% runnings of the distillate had a gravity of 80.7° B. The naphtha hydrocarbons have been found to be mainly at least of a saturated character, exhibiting small heating effect, as compared with naphtha produced in the ordinary cracking of crude petroleum, when shaken up with sulfuric acid of 66° B. If it should be desired to collect an oil consisting wholly of hydrocarbons having boiling points up to 350° F. (useful as fuel in gasoline explosive engines) the yield might be between five and ten per cent. by volume more than that of the naphtha mentioned.

From a finished burning oil (kerosene) obtained from crude petroleum of California

free from paraffin wax and having a gravity of 40.3° B., which consisted over thirty per cent. of hydrocarbons with boiling points above 450° F. and which, if distilled in the 5 usual way in a laboratory flask, would give first runnings equal to five per cent. by volume having a gravity of 51.9° B. there has been obtained (using about 7% by weight of anhydrous aluminum chlorid and working 10 in a small way) a yield of nearly twenty seven per cent. by volume of naphtha of 57.7° B. gravity, composed wholly of hydrocarbons with boiling points up to 302° F. (first runnings equal to five per cent. by 15 volume of the oil operated upon having a gravity of 71° B.) and about sixty per cent. of burning oil (kerosene) distillate over ninety five per cent. of whose hydrocarbons had boiling points not exceeding 450° F. 20 From finished burning oil (kerosene) of low grade and about 45.3° B. gravity obtained mostly from Pennsylvania and Lima crude petroleum (in part from each), using about 7% by weight of aluminum chlorid 25 and working in a small way, about 24.5% by volume of naphtha of 68.7° B. distilling over up to 302° F. (first 5% runnings 81.7° B.) was obtained and over 61.5% by volume of burning oil (kerosene) distillate, more than eighty five per cent. of 30 whose hydrocarbons had boiling points not exceeding 450° F. The oil operated upon contained some paraffin wax; it consisted more than fifty per cent. by volume of hydrocarbons with boiling points above 450° F.; and the first 5% runnings had a gravity of 60.3° B.

The temperatures of the oil in distillation and other things will vary considerably, according to the character of the starting material and other circumstances. In a small scale test run (which was made subsequently to the filing of the application for the present patent by way of example in order to illustrate a particular case in detail and in which a charge of 2,500 cubic centimeters of a gas oil of 34.4° B. gravity was distilled with anhydrous aluminum chlorid to dryness) the oil in distillation showed 45 a temperature of 315° F. when distillate commenced to flow from the condenser outlet (about an hour and twenty five minutes after commencement of firing) and a temperature of nearly 700° F. when less than 50 one per cent. of obtainable distillate remained in the still (about eleven hours and forty five minutes later). The observed temperature of the vapors passing over to be condensed as distillate was 200° F. when 55 distillate commenced to flow from the condenser outlet and 470° F. when the oil had been distilled to the above mentioned state of approximate dryness. In this test run one hundred and fifty grams of anhydrous aluminum chlorid (equal to seven per cent.

by weight of the original still charge) were employed, the whole being introduced at the start. The distillate was collected in sixteen fractions, each equal to five per cent. by volume of the original still charge, and 70 a final fraction of 72/100 of one per cent. The residue (coke and aluminum chlorid) left in the still weighed 389 grams. Some of the aluminum chlorid passed over with the vapors which were condensed as distillate. The first of the following tables (Table A) shows the gravities of the several fractions, the respective temperatures of the oil in distillation and the vapors passing over to be condensed as distillate at the 75 close of each collection, and the time occupied in each collection. The second table (Table B) gives the results of assays of the several 5% fractions of distillate and shows the percentages of each fraction with boiling points up to 302° F., 350° F., 450° F. and 572° F., respectively. This table also shows (1) the final temperature of the vapors in the flask neck in each assay in which such final temperature was below 572° F., (2) the percentage of oil remaining in the flask at the close of the assay in each case in which the vapors in the flask neck attained a temperature of 572° F., and (3) the percentage of loss in each assay. 80 90 95

An assay of a specimen of the gas oil 130

charged (34.4° B. gravity) showed the following percentages:

Boiling points up to 302° F.	1.5%
Boiling points up to 350° F.	2.0%
Boiling points up to 450° F.	3.5%
Boiling points up to 572° F.	13.5%
Residual oil in flask at 572° F.	86.0%
Loss	0.5%

- 10 Instead of operating upon distillate, use may be made of petroleum in undistilled forms, as crude petroleum, or residues from reduction (partial distillation) of crude petroleum with or without injection of superheated steam into the oil; but it is considered less advantageous to operate upon undistilled petroleum than upon distillates on account of the larger proportion of carbon in the former.
- 20 Gas oil yields more carbon than burning oil (kerosene). A considerable amount of gas and light vapors, which would escape condensation in the ordinary water cooled condenser, would also be formed in any case.

Distillates of higher boiling hydrocarbons than those of the gas oil or fuel oil mentioned (such as heavy paraffin distillate or pressed paraffin distillate, or even residue from partially distilling pressed distillate) can be operated upon; but it is considered that to do so would be less advantageous than to operate on gas oil or fuel oil, or low grade burning oil (kerosene) (finished oil or untreated distillate). The distillates obtained in reducing pressed paraffin distillate can be operated upon; and, in fact, the lighter portion of such distillate (when available) commonly forms part of the gas oil or fuel oil mentioned. So-called acid oil, obtained in known ways from acid sludge from treating burning oil (kerosene) distillate and lubricant stock (one or other, or both) with sulfuric acid (usually acid of 66° B., sometimes stronger) can be operated upon, alone or in mixtures. Hydrocarbon oils which are not forms of petroleum, but have a suitably close relation thereto, such as shale oils and the like, can be operated upon.

The fractionation of the distillate from the distillation with anhydrous aluminum chlorid, instead of being performed wholly in a distinct distillation, may be performed at least in part in the distillation with anhydrous aluminum chlorid by means of a partial condensation or a series of partial condensations of the vapors. Condensate or one or more condensates from such partial condensation or condensations can be returned to the oil in distillation or can be collected as distillate, as may be preferred. The partial condensers (one or more) may be air cooled or liquid cooled. They may receive the vapors at or near the bottom, so

that these pass in opposite directions in contact with retrograding condensate; or they may receive the vapors at or near the top, so that the vapors, as well as the condensate, travel downward.

The distillation with anhydrous aluminum chlorid is not necessarily performed by charging a still and then running off the charge. It may be performed in a more or less continuous manner. Oil might be supplied to the charge in the still while the distillation is going on, with or without addition thereto of anhydrous aluminum chlorid, and with or without the withdrawal of residual oil during the run. Continuous stills of any known or suitable form can be used.

Distillate from the distillation with anhydrous aluminum chlorid can be treated with sulfuric acid and alkali prior to fractionation by further distillation; but it is considered better to apply such treatment to fully fractionated oils.

Other materials not inconsistent with the action of the aluminum chlorid on hydrocarbons can, of course, be used in addition thereto. Anhydrous perchlorid of iron (Fe_2Cl_6), if used in addition to the anhydrous aluminum chlorid, is believed to combine with the latter and so to form a double chlorid of iron and aluminum; which acts similarly to the aluminum chlorid; although a difference in reaction has been observed; and probably a number of other substances would act similarly. In naming aluminum chlorid, therefore, in the hereinafter written claims, it will be understood that double chlorid of iron and aluminum and other similarly acting substances are intended to be included and not excluded by such recital.

In stating in the hereinafter written claims that the petroleum or related oil is to be "in any appropriate form", it is to be understood that gas oil or fuel oil, burning oil (kerosene) or other like form is primarily but not necessarily exclusively intended.

In consequence of official requirement of division, an application (officially numbered 186,542), for part of the subject-matter set forth hereinabove, was filed August 16, 1917, as a division and continuation of the application for the present patent.

On July 14 and October 4, 1919, applications (officially numbered 310,875 and 328,578, respectively) were also filed for part of the subject-matter hereinabove set forth. Each of them is a continuation of the application for the present patent; and each of them, moreover, has been made under section 4897, Revised Statutes, for the invention or discovery of my said divisional application No. 186,542, allowed October 6, 1917.

I claim as my invention or discovery:

1. The process of making low boiling oil

from higher boiling petroleum or related oil, consisting in distilling petroleum or related oil in any appropriate form with anhydrous aluminum chlorid in solution in a part of 5 the oil operated upon, and conducting operations in such manner that practically the entire carbon content of the oil operated upon, except the portion which escapes as gas or as uncondensed vapors or is otherwise 10 lost, is obtained the main part thereof in the form of distillate from distillation in the presence of said anhydrous aluminum chlorid and the remaining smaller part of 15 said carbon content in the form of coke, substantially as described.

2. The process of making low boiling oil from higher boiling petroleum or related oil, consisting in distilling petroleum or related oil in any appropriate form with anhydrous aluminum chlorid in solution in a part of the oil operated upon at least until the residue approximates the lowest point at which it can be freed from aluminum by 20 boiling with water, substantially as described.

3. The process of making low boiling oil from higher boiling petroleum or related oil, consisting in distilling petroleum or related oil in any appropriate form with a 25 limited proportion, not more than about ten per cent. by weight, of anhydrous aluminum chlorid in solution in a part of the oil operated upon, conducting the distillation with such regulation of the fires as to maintain a 30 good flow of distillate from the condenser outlet by reason of the rising temperature of the oil operated upon, and continuing the distillation with rising temperature in said oil at least until the residue approximates 35 the lowest point at which it can be freed from aluminum by boiling with water, substantially as described.

4. The process of making low boiling oil from higher boiling petroleum or related oil, 40 consisting in distilling petroleum or related oil in any appropriate form with anhydrous aluminum chlorid in solution in a part of the oil operated upon until the residue is reduced to an at least approximately dry condition, substantially as described.

5. The process of making low-boiling oil

from higher boiling petroleum or related oil, consisting in distilling petroleum or related oil in any appropriate form with a limited proportion, not more than about ten per 55 cent. by weight, of anhydrous aluminum chlorid in solution in a part of the oil operated upon, conducting the distillation with such regulation of the fires as to maintain a good flow of distillate from the condenser 60 outlet by reason of the rising temperature of the oil operated upon, and continuing the distillation with rising temperature in said oil until the residue is reduced to an at least approximately dry condition, substantially 65 as described.

6. The process of making low-boiling oil from higher boiling petroleum or related oil, consisting in distilling petroleum or related oil in any appropriate form with anhydrous 70 aluminum chlorid in solution in a part of the oil operated upon, conducting the distillation with such regulation of the fires, as to maintain a good flow of distillate from the condenser outlet by reason of the rising 75 temperature of the oil operated upon, and continuing the distillation with rising temperature in said oil until at least approximately the end of the run, substantially as described.

7. The process of making low-boiling oil from higher boiling petroleum or related oil, consisting in distilling petroleum or related oil in any appropriate form with a limited proportion, not more than about ten per 80 cent. by weight, of anhydrous aluminum chlorid in solution in a part of the oil operated upon, conducting the distillation with such regulation of the fires as to maintain a good flow of distillate from the condenser 85 outlet by reason of the rising temperature of the oil operated upon, and continuing the distillation with rising temperature in said oil until at least approximately the end of the run, substantially as described.

In testimony whereof I affix my signature in presence of two witnesses.
